COIN CHANGING MACHINE

Jerome E. Hagstrom, Kansas City, Mo., assignor
to C. Earl Hovey, Kansas City, Mo., trustee

Application December 2, 1940, Serial No. 368,130

7 Claims. (Cl. 194—79)

This invention relates to coin changing equipment of the character adapted for disposition where the public may manipulate the same and where an attendant need not be present to supervise the delivery of the change for coins introduced to the machine.

One of the important aims of this invention is to provide relatively simple, inexpensive and durable mechanism in the nature of a coin changing machine, which mechanism is capable of selectively delivering a predetermined number of coins of a given denomination after one of a number of coins of greater denomination is dropped into the machine to condition the same for manual manipulation.

More specifically, this invention relates to coin changing equipment from which may be fed a number of coins of a given denomination after the coin to be changed is inserted, the means for feeding coins from the machine being common to all coins inserted thereto and formed to travel through paths of different lengths, depending upon the denomination of the coin inserted and to be changed.

This invention has for a definite object, the provision of coin changing equipment capable of delivering two nickels when a dime is inserted, and five nickels when a quarter is inserted into the machine to render the same operative; such equipment being particularly useful in connection with vending machines for packaged goods where the vending machine is operable only after the insertion of a nickel; it being one of the major problems of the vending machine business to supply proper change at the point of purchase.

The particular manner in which the coins to be changed are disposed in the manually operable mechanism and the precise form of many of the parts of the coin vending machine embodying this invention, constitute minor objects thereof and the same will become apparent during the course of the following specification, referring to the accompanying drawings wherein:

Fig. 1 is a front elevational view of a coin changing machine made in accordance with the present invention and showing the mechanism thereof without a portion of the enclosing case.

Fig. 2 is a horizontal cross sectional view taken on line II—II of Fig. 1.

Fig. 3 is a vertical sectional view taken on line III—III of Fig. 2.

Fig. 4 is a similar sectional view taken on line IV—IV of Fig. 2 and looking in the direction of the arrows.

Fig. 5 is a fragmentary detailed sectional view through a portion of the machine taken on line V—V of Fig. 2.

Fig. 6 is a horizontal cross sectional view through the coin changing machine taken on line VI—VI of Fig. 1; and

Fig. 7 is a perspective stretch-out view illustrating several of the parts employed in the machine for receiving the coin to be changed and delivering the coins constituting said change.

5 Because the machine embodying the broad concepts of this invention is to be located in a public place, the mechanism thereof should be securely housed in a sectional case, the base of which should be secured directly to a vertical supporting surface such as the wall of a building.

10 The cover 12 is hingedly carried by base 10 and provided with a key operated latch 14 of conventional design. Cover 12 is provided with coin slots 16 through which either a dime or a quarter 18 and 20 respectively may be introduced into coin chutes 22 and 24.

15 An operating handle 26 slidably carried by cover 12 extends through a slot 28 therein and into engagement with slide 30, operably mounted 20 between a pair of opposed tracks 32. A bifurcated laterally projecting ear 34 engages pin 36 on bar 38 of parts to be more fully hereinafter described. The bifurcated end of ear 34 permits moving cover 12 to and from the normal position 25 without employment of special equipment. No part of the cover 12 is attached to the mechanism of the machine, other than through the bifurcated ear 34.

20 All of the parts of the apparatus within the 30 housing, composed of base 10 and cover 12, are carried by brackets 40 riveted or otherwise fastened to base 10 and extending forwardly therefrom.

25 A platform broadly designated by the numeral 35 42, is horizontally disposed between brackets 40 and includes spaced apart flat sheet metal members 44 and 46.

30 Member 44 supports a plurality of magazines 48 all arranged vertically and in register with 40 openings formed through said member 44. The particular manner of arranging magazines 48 is important for the coins to be delivered are stored therein. These coins 50 are in this instance, nickels two of which are fed from the machine 45 when a dime is inserted, while five are delivered from the machine when a quarter is inserted.

35 The letter "A" designates the two magazines 48 from which nickels 50 are fed when a dime is used, and the letter "B" designates the three 50 magazines 48, the nickels from which are fed in addition to nickels from magazines A when a quarter is used.

40 Directly beneath member 44 is slidably mounted a feeder plate 52 having openings 54 there-through in register with magazines 48. Slots 56 and 58 through plate 52 register with similar slots 60 and 62 provided in member 44. These last mentioned slots 60 and 62 receive the coins 45 from conventional slug ejectors 64 and 66, the 55 nature of which need not be detailed for the 60 same are conventional and form no part of this

invention. It remains only to be stated that slug ejectors 64 and 66 will divert spurious coins or slugs through chute 68 to stall 70, where the operator may retrieve the same. It is also to this stall 70 that coins 50 are delivered through trough 72 when the machine is properly manipulated. Obviously, an opening in cover 12 allows access to stall 70.

Slide 52 is reciprocably mounted below member 44 and immediately above a cooperating member 74 that has an aperture 76 therethrough and which is cut away as at 78 to allow freedom of movement in behalf of coin holder 80.

The form of coin holder 80 is important and reference to Fig. 7 will reveal that the same is U-shaped, one leg of which is secured to plate 52 through the medium of screws 82. This normally upper leg 84 of holder 80, in addition to having openings 86 to receive screws 82, is provided with slots 88 and 90. The opposite leg 92 of holder 80 has slots 94 and 96 in opposed relation to slots 90 and 88 respectively. A depending ear 98 cooperates with flange 100 of leg 84 in maintaining the dime 18 in a vertical position after the same is dropped to a place shown in Fig. 5.

Legs 84 and 92 of holder 80 are spaced apart a sufficient distance to receive frame 102 that has a stem 104 slidably journaled in slots 106 provided in the side walls of trough 72. Stability is thereby imparted to frame 102 as it is reciprocated through a rectilinear path of travel by manual manipulation of handle 26 by the operator.

Flange 108 depending from leg 84 of holder 80 cooperates with flange 100 in confining frame 102 to a horizontal plane. Angular flange 110 along one side of frame 102, bears against the edge of leg 92 of holder 80, to assist in returning the holder and plate 52 when all of the parts are brought to a normal position at one end of their path of travel by spring 112, anchored at its one end to member 46 through the medium of ear 114, and while its other end is fastened directly to one end of rack 116. This rack 116 is integral with depending flange 118 at the free side of frame 102. As shown in Fig. 6, rack 116 engages dog 120 as movement in either direction occurs.

After the parts have started through their path of travel, they cannot be reversed until after dog 120 has reached the end of rack 116. Such expedients are conventional.

Member 46 of platform 42 has an aperture 122 provided therethrough in offset relation with aperture 76 and as will be described later, the coin fed into the machine will drop through aperture 122 into coin box 124 after the parts are moved to deliver certain coins 50 from magazines 48.

A lever 126 slotted as at 128 engages pin 130 for movement about the axis of shaft 132 journaled in bearings 134 and operably joined to yoke 136 to clear slugs or spurious coins from rejectors 64 and 66 by swinging frame 138, as is now well-known in the art. Thus, if a slug is dropped into either of chutes 22 or 24 and handle 26 forced to that end of its path of travel opposite to its normal position, the slug will be dropped from the rejector when frame 138 is moved by yoke 136. The slug will pass through chute 68 to stall 70.

Means is provided to preclude the introduction of a coin into either of chutes 22 or 24 after one coin has once been dropped thereinto and until handle 26 has been moved to clear the machine. This means is identical for each chute 22 and 24 and is actuated by lever 140 pivoted intermediate

its ends as at 142 and moved about said pivotal point when frame 138 has the lower portion thereof swung outwardly, as before mentioned.

A finger 144 pivotally mounted as at 146 on the side of the coin chute 22, for example, has the in-turned ends disposed to enter the coin chute through openings 148 and 150. Spring 152 is of the "past center" character to yieldably hold finger 144 in a position with the inturned ends 10 wherever either the coin or lever lift them. For example, when finger 144 is in the position shown in Fig. 1, and a coin is dropped into chute 22, said coin will strike the inner end of finger 144 and move the same about its pivotal point 146 to force the outer end into chute 22 through opening 148. Thus, no coin can be introduced into chute 22 until the coin first mentioned, has passed through the machine and the same cleared by the movement of the manually controllable parts, before described, which results in the pivoting of lever 140 to a position where it strikes the inner end of finger 144 to withdraw the outer end of said finger from the place where it restricts chute 22.

Another attachment is secured to slug ejectors 64 and 66 and is clearly shown in Figs. 1 and 2. This attachment insures that the machine will not operate when one of the magazines 48 is empty. Yoke 154 pivoted as at 156 is yieldably held in an inoperative position by spring 158. A laterally extending projection 160 lies in the path of travel of follower 162 that rests upon coins 50 in one of magazines 48 of group A. Fingers 164 on yoke 154 move through openings provided for the purpose into the path of travel of the coins in rejectors 64 and 66 when follower 162 engages projection 160 to overcome the force of spring 158. The coin to be changed, therefore, can be fed into the machine but it is returned through chute 68 to stall 70 so long as magazine 48 wherein follower 162 is disposed, is empty or without a sufficient number of coins 50 to hold follower 162 out of engagement with projection 160.

Coin selectors such as those shown in U. S. Letters Patent No. 2,094,788, may be employed. If so, fingers 164 move into the chute 64, illustrated in said patent, at a point above abutment M to interrupt normal passage and deflect a coin against member 68 to cause the same to drop by gravity through the discharge apparatus of the patented machine (to the left of abutment N), where chute 68 of the instant machine is entered and from whence the coin passes to stall 70.

When the machine is normally operated and a dime 18 is dropped through chute 22, finger 144 will be actuated as above mentioned, to preclude the entrance of another dime until the one introduced is fed into coin box 124. The end of the path of travel of the dime is at platform 42 and the dime rests in a vertical position between ear 98, flange 100 and within slot 96 of holder 80. With the dime in such position, handle 26 is moved against the force of spring 112 and frame 102 is carried to the right, as seen in Fig. 5, to a point where edge 166 of frame 102 strikes dime 18. From this point on to the end of the path of travel of handle 26, feeder plate 52 is being moved to the right. This movement is sufficient only to carry openings 54 beneath magazines 48 in group A thereof, to a place where they register with aperture 76 in cooperating member 74 of platform 42. The two nickels will thereupon drop through trough 72 into change stall 70. The dime will be deposited in coin box 124 through the other aperture 122 of platform 42.

If a quarter 20 is dropped into chute 24, it will travel to the vertical position shown in Fig. 5 and there rest in slots 94 and 90 of holder 80. The position of coin 20 is very close to edge 166 and as soon as handle 26 is forced to the right to move bar 38 in the direction of the arrow, shown in Fig. 1, edge 166 of frame 102 will immediately strike coin 20 and move feeder plate 52 to carry all of the openings 54 thereof across aperture 76. As these openings so move, the nickels 50 will drop into trough 72 and be made available to the operator in change stall 70.

From the foregoing, it will be clear to one skilled in the art that the coin changing machine embodying the concepts of this invention might be made to present different physical characteristics than those shown in the accompanying drawings. The important relation of parts revolving about the form of frame 102 and its action upon the inserted coins to be changed, is clear and manifestly important. The machine above described is not complicated and embodies conventional slug rejectors that may be slightly altered or supplemented to meet conditions without prohibitive expense.

Having thus described the invention, what is claimed as new and desired to be secured by Letters Patent is:

1. In a coin changing machine of the character described and adapted to deliver the proper number of coins of a given denomination when one of two other coins of another denomination is introduced into the machine, comprising a plurality of vertical magazines for the coins of a given denomination; a feeder plate of the thickness of one of the coins being delivered, provided with openings normally in register with the magazines; a platform having a pair of apertures therethrough underlying the feeder plate to support the coins in the openings of said plate; a coin holder on the feeder plate having a pair of spaced apart slots to receive the coin to be changed; a manually reciprocable operating frame in register with both slots of the coin holder to receive a coin when in either slot; and means for precluding the return of said frame to its normal position until the same has been moved through its path of travel in one direction, one side of the frame being disposed to engage a coin in the said holder to move the latter and the openings of the feeder plate over one of the apertures of the platform, one of said slots of the holder being normally a greater distance from said one side of the frame than the other whereby movement of the feeder plate is less when a coin is in said one slot than the movement thereof when a coin is in the said other slot.

2. In a coin changing machine of the character described and adapted to deliver the proper number of coins of a given denomination where one of two other coins of another denomination is introduced into the machine, comprising a plurality of vertical magazines for the coins of a given denomination; a feeder plate of the thickness of one of the coins being delivered provided with openings normally in register with the magazines; a platform having a pair of apertures therethrough underlying the feeder plate to support the coins in the openings of said plate; a coin holder on the feeder plate having a pair of spaced apart slots to receive the coin to be changed; a manually reciprocable operating frame in register with both slots of the coin holder to receive a coin when in either slot; and means for precluding the return of said frame to its nor-

mal position until the same has been moved through its path of travel in one direction, one side of the frame being disposed to engage a coin in the said holder to move the latter and the openings of the feeder plate over one of the apertures of the platform, one of said slots of the holder being normally a greater distance from said one side of the frame than the other whereby movement of the feeder plate is less when a coin is in said one slot than the movement thereof when a coin is in the said other slot, the slots of said coin holder being in register with the other aperture of the platform when the frame is at the end of its path of travel in said one direction.

3. In a coin changing machine of the character described adapted to deliver the proper number of coins of a given denomination when one of two other coins of another denomination is introduced into the machine, comprising a plurality of vertical magazines for the coins of a given denomination; a feeder plate of the thickness of one of the coins being delivered, provided with openings normally in register with the magazines; a platform having a pair of apertures therethrough underlying the feeder plate to support the coins in the openings of said plate; a coin holder on the feeder plate having a pair of spaced apart slots to receive the coin to be changed; a manually reciprocable operating frame in register with both slots of the coin holder to receive a coin when in either slot; and means for precluding the return of said frame to its normal position until the same has been moved through its path of travel in one direction, one side of the frame being disposed to engage a coin in the said holder to move the latter and the openings of the feeder plate over one of the apertures of the platform, one of said slots of the holder being normally a greater distance from said one side of the frame than the other whereby movement of the feeder plate is less when a coin is in said one slot than the movement thereof when a coin is in the said other slot, said holder being U-shaped with the slots therein being in opposed relation in the legs of said holder, said frame being reciprocably mounted between the legs of the said holder.

4. In a coin changing machine of the character described and adapted to deliver the proper number of coins of a given denomination when one of two other coins of another denomination is introduced into the machine, comprising a plurality of vertical magazines for the coins of a given denomination; a feeder plate of the thickness of one of the coins being delivered, provided with openings normally in register with the magazines; a platform having a pair of apertures therethrough underlying the feeder plate to support the coins in the openings of said plate; a coin holder on the feeder plate having a pair of spaced apart slots to receive the coin to be changed; a manually reciprocable operating frame in register with both slots of the coin holder to receive a coin when in either slot; and means for precluding the return of said frame to its normal position until the same has been moved through its path of travel in one direction, one side of the frame being disposed to engage a coin in the said holder to move the latter and the openings of the feeder plate over one of the apertures of the platform, one of said slots of the holder being normally a greater distance from said one side of the frame than the other whereby movement of the feeder plate is less

when a coin is in said one slot than the movement thereof when a coin is in the said other slot, said holder being U-shaped with the slots therein being in opposed relation in the legs of said holder, said frame being reciprocably mounted between the legs of the said holder, said coin to be changed being carried by the slots of the holder in a vertical position extending to each side of the frame.

5. In a coin changing machine of the character described and adapted to deliver the proper number of coins of a given denomination when one of two other coins of another denomination is introduced into the machine, comprising a plurality of vertical magazines for the coins of a given denomination; a feeder plate of the thickness of one of the coins being delivered, provided with openings normally in register with the magazines; a platform having a pair of apertures therethrough underlying the feeder plate to support the coins in the openings of said plate; a coin holder on the feeder plate having a pair of spaced apart slots to receive the coin to be changed; a manually reciprocable operating frame in register with both slots of the coin holder to receive a coin when in either slot; and means for precluding the return of said frame to its normal position until the same has been moved through its path of travel in one direction, one side of the frame being disposed to engage a coin in the said holder to move the latter and the openings of the feeder plate over one of the apertures of the platform, one of said slots of the holder being normally a greater distance from said one side of the frame than the other whereby movement of the feeder plate is less when a coin is in said one slot than the movement thereof when a coin is in the said other slot, said holder being U-shaped with the slots therein being in opposed relation in the legs of said holder, said frame being reciprocably mounted between the legs of the said holder, said coin to be changed being carried by the slots of the holder in a vertical position extending to each side of the frame, said platform comprising a pair of vertically spaced, horizontal walls between which said feeder plate, coin holder and frame are reciprocably carried, said coins having the edges thereof slidably engaging the lowermost wall as the frame is manually moved to carry the feeder plate to a position where the coins to be delivered are dropped through one of the apertures of the platform.

6. In a coin changing machine of the character described and adapted to deliver the proper number of coins of a given denomination when one of two other coins of another denomination is introduced into the machine, comprising a plurality of vertical magazines for the coins of a given denomination; a feeder plate of the thickness of one of the coins being delivered, provided with openings normally in register with the magazines; a platform having a pair of apertures therethrough underlying the feeder plate to support the coins in the openings of said plate; a coin holder on the feeder plate having a pair of spaced apart slots to receive the coin to be changed; a manually reciprocable operating frame in register with both slots of the coin holder to receive a coin when in either slot; and means for precluding the return of said frame to its normal position until the same has been moved through its path of travel in one direction, one side of the frame being disposed to engage a coin in the said holder to move the

5 latter and the openings of the feeder plate over one of the apertures of the platform, one of said slots of the holder being normally a greater distance from said one side of the frame than the other whereby movement of the feeder plate is less when a coin is in said one slot than the movement thereof when a coin is in the said other slot, said holder being U-shaped with the slots therein being in opposed relation in the legs of said holder, said frame being reciprocably mounted between the legs of the said holder, said coin to be changed being carried by the slots of the holder in a vertical position extending to each side of the frame, said platform comprising a pair of vertically spaced, horizontal walls between which said feeder plate, coin holder and frame are reciprocably carried, said coins having the edges thereof slidably engaging the lowermost wall as the frame is manually moved to carry the feeder plate to a position where the coins to be delivered are dropped through one of the apertures of the platform, said one aperture having a chute in communication therewith to convey the delivered coins to a point accessible to the operator.

7. In a coin changing machine of the character described and adapted to deliver the proper number of coins of a given denomination when one of two other coins of another denomination is introduced into the machine, comprising a plurality of vertical magazines for the coins of a given denomination; a feeder plate of the thickness of one of the coins being delivered, provided with openings normally in register with the magazines; a platform having a pair of apertures therethrough underlying the feeder plate to support the coins in the openings of said plate; a coin holder on the feeder plate having a pair of spaced apart slots to receive the coin to be changed; a manually reciprocable operating frame in register with both slots of the coin holder to receive a coin when in either slot; and means for precluding the return of said frame to its normal position until the same has been moved through its path of travel in one direction, one side of the frame being disposed to engage a coin in the said holder to move the latter and the openings of the feeder plate over one of the apertures of the platform, one of said slots of the holder being normally a greater distance from said one side of the frame than the other whereby movement of the feeder plate is less when a coin is in said other slot, said holder being U-shaped with the slots therein being in opposed relation in the legs of said holder, said frame being reciprocably mounted between the legs of the said holder, said coin to be changed being carried by the slots of the holder in a vertical position extending to each side of the frame, said platform comprising a pair of vertically spaced, horizontal walls between which said feeder plate, coin holder and frame are reciprocably carried, said coins having the edges thereof slidably engaging the lowermost wall as the frame is manually moved to carry the feeder plate to a position where the coins to be delivered are dropped through one of the apertures of the platform, said one aperture having a chute in communication therewith to convey the delivered coins to a point accessible to the operator, the other of said apertures of the platform being in communication with a coin box for receiving the coin being changed.
